UNITED STATES PATENT OFFICE.

LAURENCE J. McDONALD, OF PHILADELPHIA, PENNSYLVANIA, ASSIGNOR
TO JOHN C. GRAHAM, OF SAME PLACE.

DESIGN FOR FRINGE.

SPECIFICATION forming part of Design No. 13,095, dated July 25, 1882.

Application filed June 10, 1882. Term of patent 14 years.

To all whom it may concern:

Be it known that I, LAURENCE J. McDONALD, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a heading, A, to which is attached a series of pendants, B, of substantially-cylindrical contour, each composed of chenille threads twisted helically about the axis of the pendant and projecting loosely therefrom. The fringe is ornamented by a series of figures having the form of Latin crosses, each occupying portions of three or more pendants and being formed of warp-threads of a color different from the

ground or body color of the pendants, said figures being arranged in regular order throughout the length of the fringe, and being alternately reversed in position—that is to say, having their horizontal arms located adjacent to their upper and to their lower ends alternately.

I claim—

A design for fringe, consisting of a heading and a series of pendants ornamented by figures in the form of Latin crosses, of different color from the body of the pendants, and having their horizontal arms alternately reversed in relative position, substantially as set forth.

LAURENCE J. McDONALD.
